Int. Cl. D6—01

U.S. Cl. D6—48

FIG. 1

FIG. 3

FIG. 2

FIG. 1 is a perspective view of a ventilated car seat embodying my new design. The small rectangular elements schematically shown are continuous throughout the seat and backrest portions.

FIG. 2 is a side elevation thereof.

FIG. 3 is an enlarged partial sectional view on line 3-3 of FIG. 1.

The back and bottom surfaces of the car seat are plain and unornamented.

I claim:

The ornamental design for a ventilated car seat, as shown and described.
